UNITED STATES PATENT OFFICE.

WILLIAM CLARK NELSON, OF SANTA ROSA, CALIFORNIA.

REIN-HOLDER.

SPECIFICATION forming part of Letters Patent No. 592,994, dated November 2, 1897.

Application filed April 13, 1897. Serial No. 631,904. (No model.)

To all whom it may concern:

Be it known that I, WILLIAM CLARK NELSON, a citizen of the United States, residing at Santa Rosa, in the county of Sonoma and 5 State of California, have invented certain new and useful Improvements in Rein-Holders; and I do hereby declare the following to be a full, clear, and exact description of the invention, such as will enable others skilled in the 10 art to which it appertains to make and use the same.

The object of this invention is to provide an improved rein-holder which is cheap, simple, and effective, the particular construction 15 of the device permitting it to be made of but two parts, not including the rivets which secure it in place.

With the above objects in view I have constructed a rein-holder one part of which is 20 made up of a sheet or strip of metal bent to form a loop to embrace the edge of the dashboard and an open frame, the other part of the device presenting a plate having pins by which it is pivoted in the open frame of the other 25 part of the device, all as will be hereinafter fully set forth, and specifically pointed out in the claim.

In the accompanying drawings, forming 30 part of this specification, Figure 1 is a perspective view showing the application of my invention. Fig. 2 is a detail view of the rein-holder, and Fig. 3 is a detail view with the parts separated.

Referring to the drawings by numerals, 1 35 designates the main part of the rein-holder, which is made up of a strip of sheet metal, one end of which is bent into a loop 2, from which it is bent outwardly at an angle and then formed into a rectangular frame presenting the side pieces 3 3, the terminal of 40 the strip being located opposite the bend or angle 4, leaving a space or opening communicating with the interior of the frame. In connection with the slanting portion of the 45 part 1 the terminal opposite thereto is flared outwardly, as shown, thereby forming guides which lead to the opening communicating with the frame. The opposite members of the loop 2 are provided with apertures or 50 holes to receive rivets by which the device is secured in place upon a dashboard, and the

side pieces 3 3 of the open frame are provided with opposing recesses or openings 4 to present bearings.

5 designates a plate which is provided at 55 opposite sides with projecting pins 6, and this plate is placed in engagement with the part 1 of the device by passing the pins into the openings or bearings 4 in the side pieces 3. When the plate 5 is pivoted within the frame, 60 as herein shown and described, it provides a gravity dog or catch to engage the reins and clamp the same between one end of said plate and the adjoining end of the frame. This securely holds the reins by frictional contact. 65 In placing the reins in engagement with the device they are passed through the vertical opening and first swing the plate upon its pivot and then pass in between the said plate and outer portion of the frame, which insures the proper 70 contact for clamping the reins between the parts, the plate being moved by gravity in engaging the reins. It will be noted that it is not necessary to manipulate the plate in placing the reins in engagement with the device, as the normal inclination of said plate 75 will permit the reins to bear against the inclined edge and swing the plate automatically.

By the particular construction of the device herein shown and described I provide a very cheap arrangement, which can be readily applied to the dashboard of a vehicle and in its construction can be made to present an ornamental appearance.

It will be understood, of course, that a device constructed in accordance with my invention need not be limited to the single use or application as a rein-holder, for it could be applied for other purposes—for instance, as 90 a holder for clothes-lines or as a lock for the operating-cord of a window-shade. It could be also applied to the handle of a cultivator, harrow, or other agricultural implement for holding the reins thereon.

Having thus described my invention, what I claim as new, and desire to secure by Letters Patent, is—

A rein-holder made up of two plates of metal, one of which is bent to present a looped 100 portion, and an open-ended frame adjoining the same, the terminal of the portion forming

the frame being turned outward adjoining the opening while the intermediate portion of the plate forms an inclined surface which leads to said opening; the other plate forming a pivoted gravity-dog located within the frame to one side of the opening and engaging the lower end of the forward part of said frame; the looped portion of the device having bolt-holes while in opposite sides of the frame are formed bearing openings or recesses for the

gravity-dog, the parts being constructed and organized as herein shown and described.

In testimony whereof I have signed this specification in the presence of two subscribing witnesses.

WILLIAM CLARK NELSON.
